UNITED STATES PATENT OFFICE.

LOUISE TULLY, OF NEW YORK, N. Y., ASSIGNOR TO THE BUTTERICK PUBLISHING COMPANY, (LIMITED,) OF SAME PLACE.

DESIGN FOR A GIRL'S COSTUME.

SPECIFICATION forming part of Design No. 14,805, dated February 19, 1884.

Application filed December 26, 1883. Term of patent 3½ years.

To all whom it may concern:

Be it known that I, LOUISE TULLY, of the city, county, and State of New York, have invented and produced a new and original Design for a Pattern of a Girl's Costume, numbered 9,004; and I do hereby declare that the engraved prints accompanying this specification convey to any one accustomed to using paper patterns a clear understanding of how a garment made up by the pattern will appear.

The design shows a walking-skirt, an under-waist that is high at the neck and has a standing collar, and also shows an over-dress that displays loose-fitting fronts, and exhibits a button and button-hole below the waist-line, being cut away above and below the closing,

and draped to fall in points by plaits in its back edges, a half-fitting back that exhibits single draping plaits in its front edges and a looping at the center, coat-sleeves, and a sailor-collars that has its ends extended in tapering lapels to the closing. 20

What I claim as my invention, and desire to secure by Letters Patent, is—

The design for a girl's costume, as shown in 25 the engraved prints accompanying this specification.

LOUISE TULLY.
